W. K. Hall,

Steam Safety Valve.

No 19568.

Patented Mar. 9, 1858.

UNITED STATES PATENT OFFICE.

WILLIAM KEMBLE HALL, OF WEST HOBOKEN, NEW JERSEY.

SAFETY APPARATUS FOR STEAM-BOILERS.

Specification of Letters Patent No. 19,568, dated March 9, 1858.

To all whom it may concern:

Be it known that I, WILLIAM KEMBLE HALL, of West Hoboken, in the county of Hudson and State of New Jersey, at present residing in London, England, have invented a new and useful Apparatus for Preventing the Bursting of Steam-Boilers; and I do hereby declare that the following is a full and exact description thereof.

10 All the contrivances hitherto adopted for the purpose of providing against explosions are designed to supply water when that in the boiler has fallen to too low a level, or to open the safety valve by the pressure of steam irrespective of other circumstances. As has been illustrated by many published examples of either of these plans would induce in many instances the very accident it was designed to avoid, and there seems every 20 reason to believe a large majority of explosions are occasioned, not by a pressure of steam allowed steadily to increase until its tension is greater than the strength of the boiler, but by the negligence of the attendant 25 in permitting the level of the water to fall below the flues, exposing the plates to a high temperature and surcharging the steam with caloric far exceeding that due to its pressure. In injecting an additional supply of 30 water into the boiler when in this dangerous condition, it is thrown over the heated plates and into the super-heated steam and suddenly converted into steam of perhaps too high a tension for the boiler; and so instantaneously moreover that it operates with all 35 the momentum of a blow, and as the water necessary to produce this disastrous result may be supplied from that already in the boiler by the agitation incident to the escape 40 of steam from the opening of the, so-called, safety valve, the alarming fact is presented that the very instrument now provided for insuring against explosions may become the cause of producing one. These considerations 45 naturally and inevitably lead to the conclusion that safety is only to be attained by opening a water blow-off valve when the surface of the water has fallen to a perilous extent, for the purpose of first discharging 50 the water which is the more dangerous agent, and then the steam—operating in fact as a water safety valve placed in a more useful and less objectionable position than the present steam valve placed on the dome. 55 By thus depriving the boiler of water it might be injured and perhaps the flues de-

stroyed by the fire, but it could not be exploded.

The nature of my invention consists in providing a steam boiler with a valve communicating with the water and retained in its seat and kept closed by a rod soldered at one or more points to the heating surface of the boiler, in such a manner that when by negligence or otherwise, the surface of the water has fallen to a dangerous extent and allowed the boiler to become overheated, the valve is released by the melting of the solder or fusible metal employed to detain the rod, and opened by the pressure of the steam, and the water and steam blown from the boiler.

To enable others skilled in the art to make and use my invention, I will proceed to describe its construction and operation, reference being had to the accompanying drawing and to the letters of reference marked thereon.

The same letters in the various figures refer to similar parts.

Figure 1, is a section of an ordinary cylindrical boiler with a single internal flue, fitted with this apparatus. Fig. 2 is a side elevation of the apparatus as applied in the preceding figure.

a is a valve communicating with the water in the boiler by a pipe *b*.

c, d, e, is a rod serving as a stem to the valve *a*, made in two parts jointed at *d*, for convenience of construction, and terminating at its lower end *e*, with a button or flange. The upper end *c*, of this rod or valve stem is cut with a screw thread and furnished with a nut by which the valve may be secured tightly in its seat.

f, is a cup, bolted or otherwise fastened to the upper portion of the flue, into which the valve stem *c, d, e*, is secured with tin or any other readily fusible metal, alloy or compound. When the tin in the cup *f*, is melted, the valve *a* is opened by the pressure of the steam and the water and the steam discharged from the boiler through the pipe *b*. The cup *f*, should be made of copper or other good conductor of heat and should be placed in the position first exposed to the action of the heat by the falling of the surface of the water, or in any other position, where, by malformation of the boiler or otherwise the plates are most likely to become unprotected by water from the action of the fire.

g, is a washer of vulcanized india rubber placed under the nut on the valve stem by which the valve is secured to its seat, for the purpose of compensating by its elasticity 5 for any difference in the expansion of the boiler and its flue and the valve stem.

h, is a pipe by which the water and steam when discharged from the boiler may be employed to extinguish the fire or conducted 10 to any suitable place. The pipe *h* may also be used as the inside feed pipe from the force pump.

Fig. 3 represents the application of my invention to a boiler with external flues. 15 Fig. 4 shows its arrangement when applied to a boiler with two internal flues. Figs. 5 and 6 show a form of the cup for holding the fusible metal with which the valve rod is secured differing from that shown at *f* in 20 Figs. 1 and 2. Fig. 7 is a modification of the joint *d* in the valve rod *c d e* by which the inequality of expansion may be compensated by the elasticity of the joint pin independent of the ring of india rubber represented at *g* in Fig. 1. The same purpose 25 may be accomplished by an ordinary helical spring.

I am aware that Cadwallader Evans in April 1839 invented an arrangement by 30 which the melting of a plug allowed the steam to escape and caused a weight to fall

and open a cock by which water from a reservoir might extinguish the fire; that John P. Bakewell in December 1839 patented an apparatus by which the steam only was blown 35 from the boiler on the melting of a plug; and that in May 1855 A. M. Glover proposed an apparatus by which an over pressure of steam when the boiler had a full supply of water would force some of the water 40 into the furnace, and when the water became low in such a case would permit the escape of steam; thus occasioning in various ways the premature escape of steam which my apparatus is designed to prevent, and 45 which in many instances seems to have been the final link in the chain of circumstances leading to the apprehended disaster. But

What I do claim as my invention and desire to secure by Letters Patent is— 50

The combination of a valve, fusible metal, and intervening elastic substance, and a pipe leading from the lower part of the boiler, as described, by which the water may first be discharged from a boiler when dangerously 55 overheated, and employed if desired to extinguish the fire.

WILLIAM KEMBLE HALL.
